UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A SPOON.

SPECIFICATION forming part of Design No. 21,741, dated August 2, 1892.

Application filed June 18, 1892. Serial No. 436,589. Term of patent 3½ years.

To all whom it may concern:

Be it known that I, HENRY L. WALLACE, of Wallingford, in the county of New Haven and State of Connecticut, have invented a new
5 Design for a Spoon; and I do hereby declare the following, when taken in connection with accompanying drawing, to be a full, clear, and exact description of the same, and which said drawing constitutes part of this specification,
10 and represents a face view.

This invention relates to a design for the handle of spoons, forks, and like articles of table-service; and the design consists in the
15 ornamentation of the handle, as shown in the accompanying illustration. The ornamentation represents a border springing from a scallop-shaped tip and running down each side the handle, terminating at the bowl in a leaf-like ornament extending down onto the bowl, the
20 border representing a scrollwork projecting from the edge onto the surface, and about

midway of the length of the handle a branch projects from one side across, and so as to give the appearance of a plain panel above, onto which the scrollwork from the borders appears to project, and one branch of the scrollwork on one side of the handle is represented as projecting inward onto the said panel, the outline of the handle corresponding to the outline of the scrollwork, as shown in the accompanying illustration. 25
30

I claim—

The design for a spoon, as herein shown and described.

In testimony whereof I have signed this 35 specification in the presence of two subscribing witnesses.

HENRY L. WALLACE.
